TOURNIQUET CLAMP

Wolfgang Ramien, Kolin-Hohenberg, Germany, assignor
to Prämeta Verkaufsgesellschaft G. Bauman & Co.,
Kolin-Hohenberg, Germany, a firm

Application April 4, 1956, Serial No. 40,894

Term of patent 14 years

(Cl. D83—1)

Fig. 1 is a front perspective view of a tourniquet clamp, embodying my new design, the portions shown in broken lines being for purposes of illustration only, and

Fig. 2 is a rear perspective view thereof.

I claim:

The ornamental design for a tourniquet clamp, as shown and described.
